United States Patent Office

Des. 211,565
Patented July 2, 1968

211,565

BOTTLE COVER OR SIMILAR ARTICLE

Roland F. Crump, Woodland Hills, Calif., assignor to Paul-Marshall Products, Inc., Gardena, Calif., a corporation of California

Filed May 3, 1967, Ser. No. 6,935

Term of patent 14 years

(Cl. D9—259)

FIG. 1.

FIG. 2.

FIG. 3.

FIG. 4.

FIG. 5.

FIGURE 1 is a front elevational view of a bottle cover or similar article incorporating my new design;

FIG. 2 is a side elevational view thereof, the opposite side being a mirror image except for the asymmetry of the scroll at the lower portion of the bottle cover;

FIG. 3 is a rear elevational view thereof;

FIG. 4 is a top plan view thereof; and

FIG. 5 is a bottom plan view thereof.

I claim:

The ornamental design for a bottle cover or similar article, substantially as shown and described.
